RAILWAY CAR FOR TRANSPORTING VEHICLES

Jack E. Gutridge, Dyer, Ind., assignor to Pullman Incorporated, a corporation of Delaware

Filed Aug. 29, 1961, Ser. No. 66,537

Term of patent 14 years

(Cl. D66—1)

FIG. 1 is a perspective view of a railway car for transporting vehicles showing my new design.

FIG. 2 is a side elevational view of the car with the doors in closed position.

The side and end of the car not shown in the drawing are substantially the same as those shown.

The essential features of my design reside in the portions shown in full lines with the automobiles shown in broken lines being included for illustrative purposes only. The racks not completely shown are conventional.

I claim:

The ornamental design for a railway car for transporting vehicles, substantially as shown and described.
